UNITED STATES PATENT OFFICE.

BARTHOLOMEW T. TREAHY, OF DETROIT, MICHIGAN.

PNEUMATIC ACTION.

968,291.

Specification of Letters Patent. Patented Aug. 23, 1910.

Application filed June 29, 1908. Serial No. 439,543.

To all whom it may concern:

Be it known that I, BARTHOLOMEW T. TREAHY, a citizen of the Dominion of Canada, residing at Detroit, in the county 5 of Wayne and State of Michigan, have invented certain new and useful Improvements in Pneumatic Actions, of which the following is a specification.

This invention relates to expression devices for automatic instruments such as 10 pneumatic piano players and has for its object to provide improved means for accentuating any note or number of notes produced in the operation of such players.

15 The device is applicable to any pneumatic player action using a controlling valve or gate to change from the full to restricted tension or exhaust, or vice versa.

The invention is illustrated in the accompanying drawings, in which—

Figure 1 is a vertical cross section of an action with the invention applied thereto. Fig. 2 is a vertical longitudinal section of the same. Figs. 3 and 4 are enlarged details of the controlling valve. Figs. 5 and 25 6 are enlarged details of the operating valve and its pneumatic. Fig. 7 is a detail in section of an intermediate valve box.

Referring specifically to the drawings, 30 indicates a tracker board over which the music sheet passes and which has an opening at each side of the regular air passages which openings are connected by tubes A and B to the controlling valve, the tube A, 35 say, for the bass register and the tube B for the treble. The valve, which is a piston valve indicated at 7, has ports controlling both tubes, the valve being operated by a knob C. The ports of said valve are connected by tubes A' and B' to valve boxes, 40 of which there are two, one for the bass and one for the treble. Only one is shown, and a description of one will answer for both. Said tube, A', is connected to a pneumatic 45 D in a compartment M in a valve box 8, which compartment is connected by a tube L to the main vacuum chest 9 of the bellows action. The pneumatic D, located in chamber M, operates a flap valve 10 covering a port 11 between the compartment M and an upper compartment N in the valve box 8, and said flap valve 10 also carries a disk valve 12 controlling an opening 13 in the top of the valve box. The upper compartment N is connected by a tube K to a

pneumatic H which is connected to and controls the valve G which is located in the main valve box 14 through which air is exhausted from the action via pipe 15. The valve G controls the pipe 16 through which direct communication is had between the action and the main exhaust, indirect or regulated communication being had through pipe 17 by the well known automatic regulator. When the valve 7 is closed the accentuating devices herein described are cut out, or inoperative, and the instrument operates as usual, that is, as if no pneumatic accentuating devices existed, with either direct exhaust through the pipe 16 or indirect or regulated exhaust through the pipe 17, valve G being accordingly opened or closed by lever 19 and connections, as desired.

To put the autopneumatic accentuating devices into condition for action, the valve G is first closed by throwing lever 19 which places action under indirect or regulated exhaust through tube 17 and the ordinary governor. The knob C being then drawn 80 places pneumatic H in line of action so it can open valve G at any desired point and thereby throw in the full tension and cause accentuation. When valve 7 is open the air entering through the perforations of the 85 music sheet passes through the tubing A and A' and B and B' and (on one side) to the pneumatic D which being in the vacuum space M thereby obtains relief and becomes inflated, in which position it opens 90 valve 10 and closes valve 12 which operation converts the chamber N into a vacuum chamber by reason of its connection through the opening 11 with the chamber M, and said chamber N being now in vacuum and 95 connected with the pneumatic H by the tube K, exhausts or deflates said pneumatic which, in turn, opens the valve G which connects full or unrestricted exhaust to the action, thereby accentuating the particular 100 note or notes struck at that time.

It will be understood that the perforations for producing an accentuated note or notes will be made at the proper places in the note sheet to uncover or open the tubes 105 A and B at the proper time.

The lever 19 is connected to valve G by a lifting crank 20 working through the side of the valve box 14. The spring 18 is merely 110 to seat the valve snugly or assist gravity.

2
The pneumatic D is deflated by the usual small bleed passage to the exhaust chamber M.

I claim:

- 5 In an auto-pneumatic musical instrument, having an action and a main exhaust the combination, with a tracker; of a valve box having a ported partition therein, to divide the interior of the box into upper and lower compartments, the top of said box having a port communication with the atmosphere; a pneumatic located in the lower compartment; direct duct communications between said tracker and pneumatic through said lower compartment; a valve located in the upper compartment and directly connected to said pneumatic for controlling the port in said partition; a secondary valve located in said upper compartment and directly connected to the first named valve, for controlling the atmospheric port; a valve cas-

ing located immediately in the line of duct communication; a valve movable within said casing for controlling the passage of air to said pneumatic; a vacuum chest in communication with said lower compartment; a pneumatic in direct duct communication with said upper compartment; a main valve box having a pipe connection with the action, and direct and regulated pipe connections with the main exhaust and a tension valve located in the main valve box and directly connected to the last-mentioned pneumatic, said tension valve controlling the exhaust through said direct pipe communication. 25 30 35

In testimony whereof I affix my signature, in presence of two witnesses.

BARTHOLOMEW T. TREAHY.
